PARKER B. HASKELL, OF LYNN, MASSACHUSETTS, ASSIGNOR OF ONE-THIRD TO WALTER B. POHLE, OF LYNN, MASSACHUSETTS, AND ONE-THIRD TO SUSAN V. RUSSELL, OF CHELSEA, MASSACHUSETTS.

SPLASH TROUGH.

Application filed February 6, 1925. Serial No. 7,333.

This invention relates to splash troughs for internal combustion engines and has for its object the provision of means for removing the sediment from each of said troughs without disturbing either of the other troughs.

This object is attained by the mechanism illustrated in the accompanying drawings:

For the purpose of illustrating the invention, one preferred form thereof is illustrated in the drawings, this form having been found to give satisfactory and reliable results although it is to be understood that the various instrumentalities of which the invention consists can be variously arranged and organized and the invention is not limited to the precise arrangement and organization of these instrumentalities as herein shown and described except as required by the scope of the appended claims.

Of the drawings:

Figure 1 represents a vertical transverse section of a crank casing provided with a plurality of splash troughs and a sediment removing device embodying the principles of the present invention.

Figure 2 represents a vertical section of the same on line 2, 2 on Fig. 1, and

Figure 3 represents an elevation of one end of the casing and showing the means for inverting the sediment collector.

Similar characters indicate like parts throughout the several figures of the drawings.

In the drawings, 10 is a crank casing for internal combustion engines provided with a plurality of splash troughs 11 which are shown as formed integral therewith.

Each splash trough 11 has an oil-containing compartment 12 therein from the bottom of which extends a passage 13 through which the oil may be discharged into the bottom 14 of the casing 10.

Each trough 11 also has formed therein a cylindrical chamber 15 extending transversely of said passage 13, this chamber having disposed therein a cylindrical member 16 having a plurality of depressions or pockets 17 therein, each communicating with the upper end of a passage 18 when the member 16 is in its normal position.

When the member 16 is in this position the sediment in the oil collects in the various depressions or pockets 17, leaving the oil clear

in the compartments 12 and through this oil passes the ends of the cranks 18 during each revolution of the shaft 19 to which said cranks are secured.

The outer end of each crank 18 is pivotally connected to a connecting rod 20, and this pivotal connection is thoroughly lubricated as it passes through the oil in the compartment 12.

One end of the member 16 extends through a wall of the casing 10 and has secured thereto an arm 21 normally locked to the casing 10 by a bolt 22.

By removing the bolt 22 the operator may grasp the arm 21 and move it clockwise to impart a half revolution to the member 16.

This movement of said member 16 inverts it so that each depression or pocket 17 registers with the lower ends of the passage 13 and permits the sediment therein to be discharged into the bottom of the casing 10.

When inverted the upper part of each passage 13 is closed and will remain closed until said member 16 is returned to its normal position.

The inner end of the member 16 is positioned in the socket 23 and a stuffing box 24 is provided for the opposite end where it extends through the casing 10.

Projecting from the wall of the casing 10 are two pins 25 which limit the movement of the arm 21 in opposite direction.

As the member 16 extends through all of the passages 13, it is obvious that by imparting a partial rotation thereto the sediment in all of the depressions or pockets 17 may be discharged at one operation.

By means of this construction the sediment may be collected in the various depressions 17 and dumped therefrom as often as desired, and this may be accomplished without placing the engine out of commission.

This is of particular advantage when the engine is on a fire truck, the services of which may be required at any moment.

It is believed that the operation and many advantages of the invention will be understood without further description.

Having thus described my invention, I claim—

1. A crank casing provided with a splash trough with an oil-containing compartment therein having a discharge passage at the bottom thereof and a cylindrical chamber in-

- intersecting said passage; a member fitted to said chamber having a sediment collecting depression therein normally in register with the upper end of said passage; and means for moving said member about its axis to cause said depression to register with the lower end of said passage.
2. A crank casing provided with a splash trough with an oil-containing compartment therein having a discharge passage at the bottom thereof and a cylindrical chamber intersecting said passage; a member fitted to said chamber having a sediment collecting depression therein normally in register with the upper end of said passage; and means outside the wall of said casing for moving said member about its axis to cause said depression to register with the lower end of said passage.
- 10 3. A crank casing provided with a splash trough extending transversely thereof and having an oil containing compartment therein from the lowest part of which extends a discharge passage; a device extending transversely of said trough across said passage and having a sediment collecting pocket closed at one end, the open end of said pocket normally registering with the upper part of said passage; and means at the end 15 of said casing for inverting said device and causing the open end of said pocket to register with the lower end of said passage.
- 20 4. A crank casing provided with a splash trough extending transversely thereof and having an oil containing compartment therein from the lowest part of which extends a discharge passage; a device extending transversely of said trough across said passage

and having a sediment collecting pocket closed at one end, the open end of said pocket normally registering with the upper part of said passage; a radial arm secured to the projecting end of said device; and means for locking said arm to the casing when the sediment collecting pocket is in normal position.

5. A crank casing provided with a splash trough having an oil-containing compartment therein with a curved bottom and an open ended discharge passage extending from the lowest part of said curved bottom; a device extending transversely of the trough across said passage and having a sediment collecting pocket normally registering with the upper part of said passage, said device extending through the end wall of said casing; and means on the outer end of said device for inverting it.

6. A crank casing provided with a plurality of splash troughs each having an oil-containing compartment therein with a curved bottom and an open ended discharge passage extending from the lowest part of said curved bottom; a device extending transversely of all of the troughs across said passages and having a sediment collecting pocket normally registering with the upper part of each passage, said device extending through the end wall of said casing; and means on the outer end of said device for inverting it.

Signed by me at 746 Old South Bldg., Boston, Mass., this 3rd day of February, 1925.

PARKER B. HASKELL.
